UNITED STATES PATENT OFFICE

136,855

DESIGN FOR A PROTECTING FERRULE FOR BOILER FIRE AND SMOKE TUBES

Konstantinos Markesinis, Barry Dock, England

Application January 27, 1943, Serial No. 109,351
In Great Britain January 26, 1942

Term of patent 14 years

To all whom it may concern:

Be it known that I, Konstantinos Markesinis, a subject of the king of Greece and a resident of Barry Dock, in the county of Glamorgan, in the Kingdom of England, have invented a new, original, and ornamental Design for a Protecting Ferrule for Boiler Fire and Smoke Tubes, of which the following is a specification, reference being had to the accompanying drawing, forming part thereof.

Fig. 1 is a perspective view of a protecting ferrule for boiler fire and smoke tubes showing my new design;

Fig. 2 is a vertical sectional view taken substantially through the center thereof; and

Fig. 3 is an end elevational view thereof taken from the right of Fig. 1.

The characterizing features of my design reside in the protecting ferrule for boiler fire and smoke tubes, having an inner tubular portion with longitudinal slits, a flange at one end of said tube, an outer shorter tubular portion concentrically mounted on the flange and lugs formed thereon, all substantially as shown.

I claim:

The ornamental design for a protecting ferrule for boiler fire and smoke tubes, as shown and described.

KONSTANTINOS MARKESINIS.
